UNITED STATES PATENT OFFICE.

JOHN R. ALLEN, OF CHICAGO, ILLINOIS, ASSIGNOR TO STACKHOUSE & ALLEN, OF CHICAGO, ILLINOIS, A PARTNERSHIP CONSISTING OF JOHN H. STACKHOUSE AND JOHN R. ALLEN.

SOCKET.

Application filed July 6, 1920. Serial No. 394,281.

To all whom it may concern:

Be it known that I, JOHN R. ALLEN, a citizen of the United States, residing at Chicago, in the county of Cook and State of Illinois, have invented a certain new and useful Improvement in Sockets, of which the following is a full, clear, concise, and exact description, reference being had to the accompanying drawings, forming a part of this specification:

This invention relates to sockets for electric lights and more particularly to a lamp socket provided with a chain pull for operating the switch mounted in said socket.

In the type of the socket now in use the chain pull is provided with a guide that is held between the insulating members upon which the switch is mounted and the outer shell of the socket. This guide is made as a separate piece and is merely clamped between said insulating members and shell which provides a small part that is difficult to handle when wiring the socket.

It is a purpose of this invention to provide a chain guide for a pull socket that is permanently secured to a portion of said socket, and which does not in any way interfere with separating and replacing into position the parts of the outer shell of the socket, thus eliminating a small loose part. In order to carry out this purpose the chain guide is secured preferably to a current carrying part of the socket and it has been found particularly advantageous to secure the same to the screw shell terminal.

As the chain guide must be a "dead" part, that is, must carry no current, it is a further purpose of the invention to properly insulate the same from the current carrying part to which it is attached.

Further objects and advantages of the invention will appear as the description of the accompanying drawings, showing certain forms that my invention may take, proceeds. In the drawings in which similar parts are referred to by similar reference characters.

Fig. 1 is an end view of the socket looking toward the cap end thereof, with the cap removed;

Fig. 2 is a longitudinal sectional view of the socket, a portion of the shell and the switch mechanism being shown in elevation;

Fig. 3 is an enlarged sectional view of the

chain guide and a fragment of the screw shell showing the manner in which the chain guide is attached thereto, and

Fig. 4 is a fragmentary sectional view of the screw shell and insulators carrying the switch mechanism, and a modified form of chain guide associated therewith.

Referring in detail to the accompanying drawings Figs. 1 to 3 inclusive show one form that my invention may take and in which is shown a chain pull lamp socket comprising an outer shell 5 provided with a cap piece 6 of the usual construction. Within the shell 5 is the switch mechanism 7 mounted upon the insulators 8 and 9 preferably of porcelain. The switch mechanism 7 is of the usual type used in a chain pull switch and is operated by the chain 10.

Mounted on one of the insulators 9 is the screw shell terminal 11 of the usual construction. Separating the screw shell portion 11 and the outer shell 5 is the usual insulating lining 12.

This invention more particularly concerns itself with providing a guide for the chain 10 that is permanently carried by a current carrying part such as the screw shell terminal portion 11. The chain guide 13 comprises a bell portion 14 having a flaring opening at both the inside and the outside thereof and through which the chain 9 extends thus guiding the chain without interfering with the movement thereof in any way.

The bell portion 14 is mounted upon a base 15 having a right angular extension 16 which is secured to the end portion 17 of the screw shell in any suitable manner as by a screw 18. It will thus be seen that a chain guide is provided that extends between the insulator 9 and the outer shell 5 and is carried by the screw shell 11. As the screw shell 11 is a live or current carrying part and as it is necessary that the chain guide be dead or carry no current, insulating means must be provided between the screw shell and the chain guide. This insulating means comprises a flat fibre insulating member 19 surrounding the screw 18 and interposed between the right angular extension 16 and the end 17 of the screw shell and an insulator 20 having a portion extending between the head of the screw 18 and the end

of the screw shell 17 and having a sleeve like extension 21 surrounding the shank of the screw and extending to the insulating member 19.

- 5 An examination of Fig. 3 of the drawing will disclose that the insulating members 19 and 20 completely separate the metallic portions associated with the chain guide and the screw shell in such a way as to completely 45
- 10 insulate the same from the screw shell thus providing a chain guide that is permanently and rigidly carried by a current carrying part but that does not itself carry any current. 50
- 15 In Fig. 4 of the drawings a modified form of chain guide 13' is shown comprising a bell portion 14' and a base portion 15' having a right angular extension 16' secured to the screw shell 11 in the same manner 55
- 20 as is the form shown in Figs. 1 to 3. The base 15' is provided with an extension 22 that is adapted to bear against the side portion of the insulating member 8' to brace 60
- 25 the chain guide and preferably the insulating member 8' is provided with a recess 23 in which the extreme end portion 24 of the extension 22 may seat, thus preventing both 65
- 30 swinging of the chain guide edgewise thereof and protecting the same against any unusual strain placed thereon in handling the same when the outer shell of the socket is removed. 70
- From the above it will be apparent that a chain guide has been provided that is permanently attached to a portion of the socket 75
- 35 so that the same cannot be readily separated therefrom when the socket is assembled and which eliminates a loose part this is difficult to handle when wiring a socket. 80
- 40 Having thus described my invention I desire it to be distinctly understood that I do not intend to limit myself to the exact de-

tails shown in the accompanying drawings and described in the specification except as defined by the following claims:

1. In a lamp socket, a current carrying part, a chain guide, means for securing said guide rigidly to said current carrying part in fixed relation thereto, and means for insulating said guide from said current carrying part. 45

2. In a device of the character described, a metallic current carrying part, a chain guide, means for clamping said guide rigidly to said current carrying part in fixed relationship thereto, and means for insulating said guide from said current carrying part. 55

3. In a lamp socket of the character described a current carrying part, a metallic chain guide, a screw for clamping said guide to said current carrying part of said socket, an insulating member between said chain guide and current carrying part, and an insulating member surrounding the shank of said screw and extending between the head thereof and said current carrying part to insulate said chain guide from said current carrying part. 60

4. In a lamp socket of the character described, a chain guide, means for clamping said guide to a current carrying part of said socket and an insulating member clamped between said guide and said current carrying part. 70

5. In a lamp socket of the character described, a chain guide, means for clamping said guide to a current carrying part of said socket and insulating members between said guide and said current carrying part and between said securing means and said current carrying part. 75

In witness whereof, I hereunto subscribe my name this 28th day of June, A. D. 1920.

JOHN R. ALLEN.
